UNITED STATES PATENT OFFICE

169,689

APRON OR SIMILAR ARTICLE

Joseph D. Mizrahi, Los Angeles, Calif.

Application January 12, 1953, Serial No. 23,098

Term of patent 14 years

(Cl. D3—26)

To all whom it may concern:

Be it known that I, Joseph D. Mizrahi, a citizen of the United States, residing in Los Angeles, in the county of Los Angeles and State of California, have invented a new, original, and ornamental Design for an Apron or Similar Article, of which the following is a specification, reference being had to the accompanying drawing, forming part thereof:

The figure is a front view of an apron or similar article, showing my new design.

The dominant features of the design reside in the portions shown in full lines in the drawing.

I claim:

The ornamental design for an apron or similar article, substantially as shown and described.

JOSEPH D. MIZRAHI.
